UNITED STATES PATENT OFFICE.

GEORGE B. WILLIAMS, OF CINCINNATI, OHIO.

STEAM-TRAP.

1,224,821.

Specification of Letters Patent.

Patented May 1, 1917.

Application filed February 24, 1915. Serial No. 10,306.

To all whom it may concern:

Be it known that I, GEORGE B. WILLIAMS, a citizen of the United States of America, residing at Cincinnati, in the county of 5 Hamilton and State of Ohio, have invented new and useful Improvements in Steam-Traps, of which the following is a specification:

This invention relates to improvements in 10 steam traps whereby the water of condensation may be returned to steam boilers and steam mains, heating coils, etc., relieved of all water of condensation.

In carrying out the present invention, it is 15 my purpose to provide a steam trap wherein the water of condensation will be positively discharged therefrom under steam pressure when the water level rises to a predetermined point and into which the water of 20 condensation may flow without encountering any back pressure or similar resistance.

It is also my purpose to provide a steam 25 trap wherein the steam equalizing and water discharge valves and the pressure release valve will be operated positively and effectively and float controlled so that the steam equalizing valve and the water discharge valve will be opened simultaneously when the float rises to a predetermined point, and 30 such valves closed and the release valve opened when the float drops to a predetermined point incident to the discharge of the water from the trap, the valve being positively actuated independently of the float 35 after the latter has risen or fallen.

With the above and other objects in view, the invention consists in the construction, combination and arrangement of parts hereinafter set forth in and falling within the 40 scope of the claims without departing from the spirit of the invention.

In the accompanying drawings:

Figure 1 is a view in front elevation of a 45 steam trap constructed in accordance with the present invention, parts being broken away.

Fig. 2 is a horizontal sectional view through the trap.

Fig. 3 is a fragmentary end view partly 50 in section.

Fig. 4 is a collective view showing a por-

tion of the float operated shaft, the controlling plate for the valves and the operating arm for the valves in perspective.

Fig. 5 is an enlarged side elevation showing the connections between the steam equalizing valve and the water discharge valve.

Referring now to the drawings in detail, 1 designates a casing constructed of any suitable material and having one side formed 10 with a lateral extension 2 in open communication with the interior of the casing 1. In the present instance, the outer end of the extension 2 is closed by means of a cover plate 3 bolted to the edge of the extension 15 by means of securing bolts 4 and capable of removal therefrom so that access may be had to the interior of the extension and the interior of the casing. Formed in the bottom wall of the casing 1 is an opening 5 and connected with the opening 5 by means of an appropriate coupling is an inlet pipe 6 and an outlet or discharge pipe 7. In each pipe 6, 7 is located a check valve 8 and the check valve 8 in the pipe 6 permits water of condensation to flow into the casing 1 and prevents back flow, while the check valve in the discharge pipe 7 permits the water to be discharged through the pipe 7 from the casing 1 and prevents the water from reentering 20 the casing 1 through the pipe 7. In the present instance, the connection between the inlet and discharge pipes 6 and 7 respectively and the casing is effected by means of a T-coupling and the inlet and discharge 25 pipes are disposed in a horizontal plane coaxial with one another. It is conceivable, however, that the inlet and outlet pipes may be otherwise connected with the casing and arranged in any desired positions relatively. 30

Formed in the casing 1 adjacent to the upper end thereof is a steam inlet opening 9 and connected with the steam inlet opening 9 is one end of a steam pipe 10 having the other end thereof terminating immediately 35 below the lateral extension 2 on the casing 1 and connected with branch pipes 11, 12. In the present instance, a T-coupling forms the connection between the lower end of the steam pipe 10 and the branch pipes 11 and 12 and the latter are disposed in the same 40 horizontal plane coaxial with each other.

However, the branch pipes 11 and 12 may be connected with the steam pipe 10 in any other suitable manner and otherwise arranged if desired.

- 5 In the present instance, the pipes 11 and 12 are disposed in a plane above the discharge pipe 7 parallel with the latter and located in the pipe 11 is a steam valve 13 of any suitable construction preferably of the 10 sliding gate type, while located in the branch pipe 12 is a pressure release valve 14 of any approved construction, preferably of the sliding gate type. Located in the discharge pipe 7 and controlling the flow of water therethrough is a valve 15 preferably, although not necessarily, of the sliding gate type. The valves 13 and 15 are disposed one above the other and connected to the stem of the valve 13 is a yoke 16 having the 15 lower end portion thereof connected through the medium of a rod 17 with the stem of the valve 15.

Arranged within the lateral extension 2 of the casing 1 is a horizontal shaft 18 projecting outwardly through one side of the extension 2 and working in a stuffing box 19'. Fast upon the inner end of the shaft 18 is one end of an arm 19 and connected to the remaining end of the arm 19 is a float 20 located within the casing 1. Loosely mounted upon the outer end of the shaft 18 and projecting upwardly therefrom is an arm 21 and fixed to the upper end of the arm 21 is a weight 22 normally acting to swing the arm in one direction or the other and secured to the adjacent side of the lateral extension 2 and projecting outwardly therefrom in the paths of movement of the arm 21 are stop 25 pins 23, 23 adapted to limit the swinging movement of the arm 21 under the action of the weight 22. A sector-like plate 24 is loosely mounted at its center upon the outer end portion of the shaft 18 immediately adjacent to the arm 21 and projects upwardly from the shaft and secured to the outer face of the plate 24 and projecting outwardly therefrom are pins 25, 25 disposed at the opposite sides of the 30 arm 21 in the paths of movement of the latter. Projecting outwardly from the front side of the arm 21 adjacent to the pivoted end thereof are pins 26 disposed at the opposite sides of a pin 27 secured to the outer end of the shaft 18 and projecting upwardly therefrom between the pins 26. When the float 20 moves upwardly in the casing 1 under the action of the water the arm 19 rotates the shaft 18 and in the initial 35 rotary movement of the shaft 18 the pin 27 thereon engages the topmost pin 26 and swings the arm 21 to a substantially vertical position. When the shaft 18 has revolved sufficiently to move the arm 21

slightly beyond the vertical, the weight 22 carries the arm 21 around independently of the action of the shaft 18 and float 20 and in this movement of the arm 21 under the action of the weight, such arm engages the pin 25 in the path of movement thereof on the plate 24, thereby revolving the plate 24 about the shaft, the stop pin 23 in advance of the arm 21 limiting the movement of the latter. On the other hand, when the float 20 descends incident to the discharge of the water from the casing 1 the arm 19 moves downwardly and rotates the shaft 18 in the reverse direction and in the initial movement of the shaft 18 the pin 27 thereon engages the other pin 26 on the arm 21 and swings the latter past the vertical position in the opposite direction. Immediately that the arm 21 passes the vertical the weight 22 carries such arm downwardly into engagement with the stop pin 23 and in this downward movement of the arm 21 the other pin 25 on the plate 24 is engaged by the arm and the plate 24 swung in the reverse direction.

Secured to the outer face of the plate 24 at the opposite sides of the center thereof are eyes 28 respectively and passed through the eyes 28 are the upper extremities of rods 29, 29 respectively connected with the stems of the valves 13 and 14. Threaded onto the upper end portion of each rod 29 below the eye 28 is an adjusting nut 30 and threaded onto each rod above the eye is an adjusting nut 31.

In practice, the branch pipe 11 is connected up with the steam space of the boiler or other steam container, the pipe 7 connected with the water space of the boiler and the pipe 6 connected with the boiler or other apparatus to receive the water of condensation therefrom. As the water of condensation enters the casing 1 the float 20 rises and rotates the shaft 18 to swing the arm 21 as previously described and in the movement of the arm 21 under the action of the weight 22, succeeding the rising of the float 20, the plate 24 swings about the shaft 18 with the effect to close the valve 14 and open the valves 13 and 15. When the valve 13 is open steam flows into the upper end portion of the casing 1 and so forces the water out of the latter through the pipe 7 past the valve 15. In the emptying of the casing 1, the float 20 descends and so reverses the movement of the shaft 18 and the arm 21 swings the plate 24 in the reverse direction, thereby closing the valves 13 and 15 and opening the valve 14 to place the steam space of the casing 1 in communication with the atmosphere whereby the water of condensation may flow freely into the casing without encountering back pressure or accumu-

lated pressure in the casing. The casing 1 is preferably provided with a water glass 32 whereby the height of the water in the casing may be readily ascertained at any 5 time.

In the present instance, the shaft 18 is provided with an outwardly extending arm 33 disposed diametrically opposite the arm 19 and equipped with a counterweight 34 10 adjustable on the arm 33.

From the foregoing description taken in connection with the accompanying drawings, the construction, mode of operation and manner of employing my invention 15 will be readily apparent. It will be seen that I have provided a steam trap wherein the controlling valves are actuated positively independently of the float after the latter has reached the limit of its movement to one position or the other and into 20 which the water of condensation will flow freely and from which such water will be positively discharged.

While I have herein shown and described 25 the preferred form of my invention by way of illustration, I wish it to be understood that I do not limit or confine myself to the precise details of construction herein described and delineated, as modification and 30 variation may be made within the scope of the claims without departing from the spirit of the invention.

I claim:

1. A steam trap comprising a casing having 35 a water inlet and a water outlet in the bottom thereof, and a steam inlet in the top, a valve controlling said outlet, a valve connecting said steam inlet to a source of steam pressure, a valve for placing the same 40 steam inlet in communication with the atmosphere, the first two mentioned valves being arranged in vertical alinement, a yoke forming a connection between said valves, a shaft journaled in one wall of the casing, 45 a float on one end of the shaft, a weighted arm mounted upon the opposite end thereof for oscillatory movement, means for limiting the movements of said arm, and a connection between the valves and arm to simultaneously open the first two and close 50 the last mentioned valve, and vice versa.

2. A steam trap comprising a casing having 55 a water inlet and water outlet in the bottom thereof, and a steam inlet in the top, a valve controlling said outlet, a valve for connecting said steam inlet to a source of steam pressure, a valve for placing said steam inlet in communication with the atmosphere, a shaft journaled in one wall 60 of the casing and a float on one end of the shaft, a weighted arm mounted on the other end thereof for independent oscillatory movement, spaced pins projecting from said arm, a lug rising from the shaft between

said pins and adapted to coöperate with the 65 latter to initially impart movement to said arm, and a connection between the valves and arm to simultaneously open the first two and close the last mentioned valves and vice versa. 70

3. A steam trap comprising a casing having 75 a water inlet and water outlet in the bottom thereof, and a steam inlet in the top, a valve controlling said outlet, a valve for connecting said steam inlet to a source of steam pressure, a valve for placing said steam inlet in communication with the atmosphere, a shaft journaled in one wall of the casing, a float on one end of the shaft, a weighted arm loosely mounted on the opposite end of the shaft for independent oscillatory movement, spaced pins projecting from 80 said arm, a lug carried by the shaft fitted between said pins to coöperate therewith for initially imparting movement to said arm, a plate loosely mounted on said shaft, pins projecting from said plate disposed at opposite sides of the said arm and a connection 85 between the valves and plate to simultaneously open the first two and close the last mentioned of said valves and vice versa.

4. A steam trap comprising a casing having 90 a water inlet and a water outlet in the bottom thereof, and a steam inlet in the top, a valve controlling said outlet, a valve for connecting said steam inlet to a source of steam pressure, a valve for placing said inlet in communication with the atmosphere, a shaft journaled in one wall of the casing, 95 a float on one end of the shaft, a weighted arm mounted on the other end thereof for independent oscillatory movement, spaced pins projecting from said arm, a lug rising from the shaft between said pins and adapted to coöperate with the latter to initially impart movement to said arm, means for limiting the movement of said arm in opposite directions, a sector-like plate loosely mounted on said shaft, means carried by the plate to be engaged by said arm, 100 whereby the latter imparts a movement to said plate, and spaced parallel rods depending from said plate and connected with said valves at opposite sides of said arm, whereby the first two mentioned valves are simultaneously opened and the last mentioned valves closed upon movement of the arm in one direction, and vice versa. 110

5. A steam trap comprising a casing having 115 a water inlet and a water outlet in the bottom thereof, and a steam inlet in the top, a valve controlling said outlet, a valve connecting said steam inlet to a source of steam pressure, a valve for placing said steam inlet in communication with the atmosphere, 120 a lateral extension forming part of said casing, a shaft journaled in said extension, a float on one end of the shaft, a weighted arm

on the other end thereof for independent oscillatory movement, pins projecting from said extension on the casing and arranged at opposite sides of the arm to limit the movements of the latter, a plate loosely mounted on said shaft, means carried by the plate and coöperating with said arm whereby the latter imparts movements to said plate, and a connection between said plate and said valves whereby the first two are

simultaneously opened and the latter closed on movement of the arm in one direction, and vice versa.

In testimony whereof I affix my signature in presence of two witnesses.

GEORGE B. WILLIAMS.
